UNITED STATES PATENT OFFICE.

SAMUEL STOPHLET, OF KANSAS CITY, MISSOURI.

DESIGN FOR A PUZZLE-SHEET.

SPECIFICATION forming part of Design No. 26,009, dated September 8, 1896.

Application filed July 11, 1896. Serial No. 598,903. Term of patent 3½ years.

To all whom it may concern:

Be it known that I, SAMUEL STOPHLET, of Kansas City, Jackson county, Missouri, have invented a new and original Design for a Puzzle-Sheet, of which the following is a full, clear, and exact description, reference being had to the accompanying drawing, forming a part thereof.

My invention relates to puzzles, and my object is to produce a new design for such devices, the leading feature of which consists of a series of circular or other figures connected together.

In the accompanying drawing, which illustrates in perspective my design, 1, 2, 3, 4, 5, and 6 and 7, 8, 9, 10, 11, and 12, respectively, represent two series of circular disks, each series being arranged in hexagonal form, and 13 designates a neck or bridge which connects the disks 6 and 7, and consequently the two series together.

14 designates two similar disks, which are arranged in the center of the two hexagonal series of disks, and are each connected to said surrounding disks by the necks or bridges 15 and 16, respectively. Arranged between said hexagonal series of disks, at opposite sides of the disks 6 and 7, are a pair of disks 17 and 18, and said disks are connected, respectively, by the necks or bridges 19 to the disks 6 and 7.

Having thus described the invention, what I claim as new, and desire to secure by Letters Patent, is—

The design for a puzzle-sheet, substantially as herein shown and described. 35

In testimony whereof I affix my signature in presence of two witnesses.

SAMUEL STOPHLET.
